UNITED STATES PATENT OFFICE.

LOUIS H. STEIN, OF CHICAGO, ILLINOIS, ASSIGNOR TO STROMBERG MOTOR DEVICES COMPANY, OF CHICAGO, ILLINOIS, A CORPORATION OF ILLINOIS.

UNIVERSAL MULTIPLE-OPERATION MACHINE.

Application filed September 8, 1924. Serial No. 736,419.

My invention relates to metal working machines for performing a series of operations such as drilling, counterboring, tapping, slotting, milling and the like, upon a piece or blank.

The device of my invention relates to that class of machines which are termed semi-automatic machines. There are many articles or machine elements which require a 10 number of different operations to be performed upon them. Broadly, this has been performed heretofore by the turret lathe and screw machines where the article or element has an axis of rotation common to 15 the various cuts which are made on or in it.

Now where the article is of an irregular shape or contour, having no common axis of rotation with respect to the operations to be performed, such procedure as is taught 20 by the turret lathe is not available. I have, in accordance with the present invention devised a machine for performing the successive operations by a novel arrangement of cooperating mechanisms embodying, I be- 25 lieve, a new principle. I have conceived the idea of carrying the piece or article through a definite path or circuit, and performing successive operations at successive positions. At each position a different oper- 30 ation is performed and successive pieces proceed in regular fashion through the suc- cessive positions. The chucks or work 35 holders may be permanently attached to the carrier and move through a closed path or they may be detachable and the carrier or conveyor move through the closed path. If desired the carrier or conveyor may be di- 40 vided in sections fed in regular succession through the machine. The real gist of the invention resides in the progressive and con- tinuous automatic advance in a series of steps from station to station where suc- 45 ccessive operations are performed.

The pieces are all operated on simulta- 45 neously and they all advance or are stepped forward simultaneously between operations. In order to do this most advantageously, the work upon the piece or article is so divided up that no one operation will take longer 50 than another within limits, and the lower limit as to time of operation is the time re- quired for inserting a blank into the machine and taking out a finished article or where 55 two successive positions may be devoted to these two operations the lower limit is then

the time required either for inserting the blank or for taking out the finished article during so much of the circuit as is devoted to inserting, changing, and removing the work.

This principle of dividing the work up into relatively short steps progressively carried on automatically at successive stations on different centers and all perform simultaneously and within a common period of time, is, so far as I know, broadly new. The number of operations that may thus be performed simultaneously is not limited to the number of operations upon a common center or from a common direction. The operations may be extended to any desired number within limits.

In the embodiment which I have con- 75 structed and operated and herein illustrated, all of the operations are performed by cutting tools moved in the same direction to and from the work; that is to say, in this machine the spindles are all vertical and parallel. The principle may be extended to the performance of operations in two or more planes; that is to say, the cutting tools may be set at different angular positions with respect to each other, all within the broad teaching of the present invention. But in the machine which I have constructed 80 and operated, I keep all the working heads in the same general position and to secure a cutting or forming operation upon the article in a different plane, I change the position of the work for operation in such 85 different plane or direction. I also wish to point out that the machine is not limited to one man operation, but may be extended to operation by more than one operator or attendant. In such case, the operations are 90 again all timed so that all automatic operations are timed with to be coextensive and contemporaneous with the hand operations.

Now while I have illustrated a specific piece and a specific machine for operating upon the piece, it is to be understood that the principles of my invention are not re- 100 stricted to the particular machine illustrated nor to the work upon the specific piece herein illustrated and described;

In the accompanying drawings I have 105 illustrated a specific embodiment of my invention.

Fig. 25 is a vertical sectional view taken on the line 25—25 of Fig. 2;

Fig. 26 is a fragmentary sectional view taken on the line 26—26 of Fig. 24 illustrating the ways or guides for the cutter heads;

Fig. 27 is a fragmentary section taken on the line 27—27 of Fig. 2 illustrating the adjuster for the driving pulley for driving the spindles of the operating head;

Fig. 28 is a fragmentary side elevational view of the cam and arm for controlling the timing of the working or cutter heads;

Fig. 29 is a horizontal section through the cam and timing mechanism shown in Fig. 28 and also shown on the line indicated at 75 29—29 in Fig. 2;

Fig. 30 is a horizontal section on the line 30—30 of Fig. 2.

Fig. 31 is a vertical sectional view on the line 31—31 of Fig. 2 showing the holding 80 mechanism for the vertical adjustment of the working spindles;

Fig. 32 is a horizontal section taken on the line 32—32 of Fig. 2 showing the same mechanism;

Fig. 33 is a fragmentary section taken on the line 33—33 of Fig. 2 showing the mounting for the lower ends of the rods which hold the spindle mechanisms in vertical adjustment;

Fig. 34 is a fragmentary sectional view on the line 34—34 of Fig. 2 showing the clutch for clutching the cam to its operating shaft;

Fig. 35 is a fragmentary view taken on the line 35—35 of Fig. 2 showing another detail 95 of the same;

Fig. 36 is a side elevational view and Fig. 37 a horizontal section through the upper bearing for the lay shaft for the change gear mechanism shown in Fig. 2;

Fig. 38 is a vertical sectional view through one of the operating heads showing a slotting saw;

Fig. 39 is a side elevational view of the same;

Fig. 40 is a horizontal section taken on the line 40—40 of Fig. 38;

Fig. 41 is a similar horizontal section taken on the line 41—41 of Fig. 38 showing the reducing gearing;

Fig. 42 is a diagram illustrating one cycle of operation;

Fig. 43 illustrates another cycle of operation;

Fig. 44 illustrates with a sample article 115 the diagram of operation shown in Fig. 42;

Fig. 45 is a diagram illustrating six operations to be performed as illustrated in the diagram of Fig. 42;

Fig. 46 as an isometric view of the part 120 worked upon by the machine;

Fig. 47 is a plan view of the part illustrated in Fig. 46; and

Fig. 48 is a side view of the said part.

For ease in explaining the machine here- 125 in illustrated I shall now refer to the diagrams shown in sheet 16.

On many machine elements and manufactured articles a series of operations are required to finish the same, and the particular 130

machine herein illustrated is designed to perform a number of operations successively upon successive pieces, and to this end I employ a carrier 1 which consists of a rotating disc or platen for convenience in construction and operation, although it is to be understood that the invention is not to be limited to movement in a single plane nor to movement in a horizontal direction only.

10 Assume that the disc 1 is mounted on a central spindle and is arranged to be advanced one-eighth of a revolution in steps timed according to a certain time interval t and permitted to rest in position between movements for the purpose of permitting the work to be operated upon at each station. In the example that I have chosen to illustrate there are eight successive stations corresponding to the eight positions, but it will be understood that this is merely illustrative and not limiting. Assume that the operator stands between stations 1 and 8 and that the carrier 1 has means such as chucks which will be described later, for holding pieces of work to be operated upon at points or positions equidistant angularly on the carrier 1. Assume also that at each of positions 2 to 7 inclusive an automatic operating tool is stationed, now it may be seen that if these tools are arranged in the order in which they are to operate upon the work at successive stations and that these tools are first lowered into engagement with the work simultaneously and then withdrawn, the carrier 1 may be set forward by one step and successive pieces will be fastened in the chucks at position 1 and finished articles taken off at position 8, six successive steps may be performed.

40 Now it is to be understood that the six operations which I have shown need not be performed all at the same point upon the article; for example, assume that three operations are to be performed at one point and three at another, and that these operations comprise respectively drilling, counter-boring, and tapping two holes as is illustrated in the diagram of 42. That is to say, assume that at position 2 the piece 11 is to be drilled on one center as indicated, at position 3 the hole is to be counter-bored, at position 4 the lower end of the hole is to be tapped, at position 5 another hole is to be drilled, at position 6 the second hole is to be counter-bored, and at position 7 the lower end of the second hole is to be tapped. These operations are merely illustrative and not limiting. Instead of drilling, counter-boring, and tapping and instead of operating at two points, different operations and operations at either the same point or at different points may be carried on. Where the operations are to be performed upon the piece, such as 11, from different directions I prefer to perform all of the operations in

one line, plane or direction and then rechuck the piece in a different position and then have the other operations performed. For example, in Fig. 43, I have shown the operator's station as between stations 1 and 8 and employ spindles at positions 2, 3, 4, 5, 6 and 7 only. In this case operations are carried on in one plane or one position at stations 2, 4, and 6 wherupon the pieces are rechucked and then the next step of operation is performed at positions 3, 5, and 7. It will be understood that all stations need not operate upon the piece, and as will be apparent later the positioning of the operating heads at their stations may be varied in order to secure the desired effect upon the piece of work.

The particular work to which I have applied the machine in the present instance is the drilling, counter-boring, tapping and slotting of a mixture regulating tube holder shown in Figs. 46 and 47. It will be noted that this comprises a split clamp member 12, comprising a central hole and clamping ears 13 separated by a slot. These ears are drilled, counter-bored and tapped to receive a machine screw for drawing them together in order to shrink the size of the hole in the split clamp to fasten the device upon a suitable mounting stem. The opposite end of the holder comprises also a split clamp for holding a small bored tube such as is used in a Bowden cable construction for operating a valve for a carburetor. The piece is made of a stamping of cold rolled sheet metal and a split clamp at 14 is formed by the two sides of the stamping which are slightly separated as indicated at 15 and a tubular opening is formed at the outer end of the split clamp in order to receive the cylindrical tube which is to be clamped. The two sides of the clamp 14 are drilled, counter-bored and slotted as is indicated at the hole 16.

Assume that in manufacturing the holder shown in Figs. 46, and 47 and 48, it were first desired to ream the hole 12 in a split clamp, next to mill the slot 17, then drill, counter-bore and tap the hole 16 all in the same plane or from the same position. The operations would then be laid out on the machine as shown in Fig. 44. As so laid out, five out of the seven possible positions are employed; the seventh position as numbered on Fig. 44 is idle; the eighth position is employed for releasing the finished holder, and the first position is employed for chucking the blank.

I have indicated in Fig. 45 how six operations may be performed such as drilling, counter-boring and tapping two holes which may be laid out as shown in Fig. 42 or laid out as shown in Fig. 43.

Now, the actual production of the piece shown in Figs. 46 to 48 requires two opera-

tions in two planes, since the hole 12 for the split clamp 13 is to be drilled, counter-bored, tapped and slotted, the hole 12 is not machined, this being punched in the punch press, and the hole 16 is to be counter-bored and tapped, no drilling being necessary as this hole is originally punched in the punch press. In the actual machine shown in Figs. 1 to 41, these six operations are performed, four operations while the pieces are in one position and two operations while the pieces are in another position.

The carrier and its mounting.

15 The machine shown comprises the revolving table or carrier 10, which is mounted for rotation in a horizontal plane upon a stub-shaft 20 which stub-shaft 20 (see Fig. 6) is mounted axially in alignment with and telescoped with the main shaft 21. The stub-shaft 20 has a reduced upper end, as shown at 22, Fig. 6 keyed and locked into the hub 23 of the table 10. The shaft has a bearing in the bronze bushing in 24, mounted in a box 25, forming a part of the upper frame plate 26.

20 This cylindrical bearing 24 serves to hold the table 10 radially in position and the stub-shaft 20 serves to transmit intermittent motion to the table 10 for advancing the same by a step by step motion through the intermediary of the Geneva mechanism, which is shown in cross-section Fig. 6 at 27. (The Geneva mechanism is shown in plan view 25 in Fig. 3.) The lower end of stub-shaft 20 is recessed as shown at 28 to receive the anti-friction bushing 29, which forms a bearing for the reduced upper end 30 of the main shaft 21. Upon the lower end of said stub-shaft 20, there is keyed the hub and web member 31, to which is bolted the Geneva gear 32, the cooperating Geneva pinion 33 will be described later.

25 The vertical thrust of the carrier or table 10 is supported upon a large anti-friction bearing 34, this bearing comprising a hardened ring 35 bolted as by means of the machine screws 36 to the bottom of the table 10, and comprising further a similar hardened plate or ring 37 bolted to the top frame plate 26, these rings being separated by suitable anti-friction bearings in this case shown as the ball-bearings 38. The ball-bearings 38 are guided between two hardened rings 39 and 40, these rings together with the lower ring 37 forming a suitable race way for holding the bearing roller 38. It is to be noted that this bearing 34 is disposed in such a manner as to receive most of the 40 thrust of the operating heads directly. The table 10 supports at equidistant points the eight chucks or work supports 41. The work supports shown in these drawings really constitute two chucks. They are all alike

and are interchangeable and are adapted to facilitate the chucking and unchucking or releasing of the pieces which are fed through the machine and which constitute the work.

5 The lower end of the main shaft 21 has a radial bearing in the anti-friction bushing 43 formed in the upper end of the boss or box 44, and has a thrust bearing 45 formed in the lower part of said boss or box 44. This thrust bearing comprises an upper ring or race-way 46, a lower ring or race-way 47 and anti-friction rollers 48 between said races. The lower end of the shaft 21 is reduced as indicated at 49 to fit snugly within the upper race ring 46 and to fit loosely into the lower race ring 47. The boss or box 44 has a base flange 50 which is clamped as by means of machine screws 51 upon the top plate 52 of the base member 53. A central boss 54 is formed below the box 44 to sustain the weight of the main shaft. The base 53 has a suitable clamping or bolting flange for mounting the machine upon the floor. A frame in the shape of a barrel or housing 55, extends up from the base plate 52 to the top plate 26. The table or carrier 10 has a downwardly extending flange or skirt 55, which overhangs the edge of the top plate 26 and prevents the entry of dirt and foreign matter, and particularly protects the bearing 34. It will be noted from Figure 6 that the stub-shaft 20 is drilled as indicated at 56 to permit oiling of the radial bearing 24 and the telescope bearing 29 between the stub-shaft and the main shaft.

The working heads.

30 The working heads 57, 58, 59, 60, 61 and 62 are disposed upon the barrel or the frame housing 54 as will be more particularly described in detail later. These working heads are disposed at equiangular stations in the present instance at six of eight equidistant stations 45 degrees apart.

35 These working heads are all alike to the extent of having the same frame, driving and feeding mechanism and being all adapted to receive suitable working tools which may be varied as desired to perform the particular operations.

40 Referring now to the operating head at 59 which is shown in side elevation in Fig. 2, it will be seen that the same has a goose neck frame 63 bifurcated at its upper end 64 to receive the central driving pulley 65. At its lower end the goose neck frame 63 has a base 66 (see Figs. 2 and 23) which is clamped upon a suitable slide or carriage 67, this carriage 67 is mounted upon a dovetailed slide member 68 which holds the carriage 67 firmly in place but permits adjustment radially with respect to the barrel and to the carrier 10. The dove-tail guide 69 fits into a corresponding recess in the carriage

67, a cooperating bearing strip 70 (see Figs. 25 and 26), being secured on the lower surface of the carriage 67.

A suitable driving pulley 71 is carried 5 with the carriage 67 to drive the pulley 65 on the spindle of operating head 59. This pulley 71 is suitably splined upon a driving shaft 72 and the pulley is carried in a forked carrier 73, which carrier has the arms 74 10 and 75 extending on opposite sides of pulley 71 and mounting the anti-friction bearings 76 and 77, these bearings moving with the forked frame 73. The frame 73 has a bracket extending upward and an attaching 15 plate 78 for bolting the frame 73 to the top of the carriage 67. This is shown in Figs. 23 to 26 inclusive. An angle bracket 79 connects the bottom surface of the carriage 67 with the arm 75 of the forked frame 73 so 20 as to secure a rigid connection between the carriage 67 and the forked frame. The supporting or guide member 68 is supported by two webs or gussets 80, which extend down from the top of said guide member 68 25 and join a clamping plate 81 which is clamped to a flat faced boss 82 formed on the barrel or frame 54.

The bed or guiding member 68 has a slot 30 in the central part thereof through which the angle bracket 79 extends for connecting the carriage 67 with the carriage for the pulley 71. Upon the bottom of the bed or guide 68, I provide a relatively stationary nut 83, which has a pin 84 extending into a 35 socket 85 and an adjusting or lead screw 86 threads through the nut 83. This lead screw extends through a boss or box 86 and has collars 87 and 88 secured upon opposite sides of the box. The outer end of the lead screw 40 89 is squared as shown at 90, to permit turning thereof for moving the carriage on the guiding bed or ways in or out radially as may be desired. The forked pulley carrier frame 73 is moved with the goose necked 45 frame, the two being formed rigidly together.

Suitable idlers 91 and 92 are mounted upon brackets 93 and 94, these brackets being clamped upon opposite sides of arms 95 50 and 96, which are preferably cast integral with the goose neck frames 63. A belt 97 is trained over the driving pulley 71, the idlers 91 and 92 and the spindle driving pulley 65. The spindle driving pulley 65 has suitable 55 anti-friction bearings in the forked frame 64 but is suitably keyed to its live spindle 98 by a feather key which permits the rise and fall of the spindle through the pulley 65.

60 *Means for raising and lowering the tool of the working head.*

Each working head has automatic means 65 for raising and lowering the cutting tool which it drives. In the particular working head 59, which is shown in side elevation

Fig. 2, the tool illustrated is a tap 99 which is suitably chucked in the lower end 100 of the spindle 98. This lower chucking portion 100 is provided with suitable mechanism not shown for backing out the tap 99 when the 70 downward stroke has been completed. This particular tapping chuck is well-known in the art and is not of my invention.

The spindle 98 has suitable anti-friction bearings, including up and down thrust 75 bearings at 101 and 102, in the quill 103 (see Fig. 28). The quill or sleeve 103 is carried in a bracket arm 104, the outer end of which is bored and slotted as is shown in Fig. 29, to receive the quill 103 and its attached rack 105. The base of the bracket 104 is provided with a dovetailed slot which is slidably mounted upon the dovetailed guide or ways 106. The bracket is adjustable on the guide 106 so as to bring the 80 working tool 99 to the proper height above the work for neutral position.

The position of the bracket 104 along the slide or way 106, is adjusted through the manual adjusting screw or lead screw 107, 90 the lower end of which is anchored in a bracket 108. The bracket 108 is in turn clamped upon the carriage 67 so as to be in effect integral with the frame of the goose neck arm 63.

The lower end of the lead screw 107 has a head 109 mounted on the lower part of the lug 110 of bracket 108, and it has a collar 111 mounted above the lug 110, this collar being formed in the shape of a capstan, having a plurality of sockets at angular positions for the insertion of a pin for turning the lead screw 107. The upper or threaded part of the lead screw extends up through a frame member 113 which is connected to the 105 bracket 104, this frame member 113 serving to mount the automatic feeding mechanism for feeding the quill 103 up and down with respect to said bracket 104 and thereby advancing and withdrawing the working tool 110 99 towards and from the table 10.

In Figs. 29 to 33 the details of this 115 manual adjustment for raising and lowering the bracket 104, are shown.

A guiding and clamping frame 114, comprising a vertical boss 115 and a clamping base member 116, is mounted upon a lug 118 forming a part of the frame 113.

The parts 115 and 118 are drilled to receive the lead screw 107. The boss 115 has a lateral extension 119 in which is guided a mutilated nut 120, this nut having a plunger 121 passing out through a manually rotated lifter or cam member 122, this lifter having a handle 123 by which it is adapted to be rotated, and having a cam surface 124 adapted to cooperate with a transverse pin 125, which pin extends through the outer end of the plunger 121. The inner end of the lifter 122 has a boss 126 which is threaded into a 125 130

socket 127 forming the outer end of the guiding extension 119. A spring 128 surrounds the plunger 121 and lies between the threaded stem or stud 126 and the nut 120. 5 The nut 120 which forms the inner end of the plunger 121 has grooves 129 formed in opposite sides thereof and guiding screws 130 have reduced inner cylindrical ends which extend into these grooves for guiding 10 the nut 120.

The nut 120 has threads cooperating with the threaded stem 107 and the spring 128 normally holds these threaded parts in engagement so that the capstan head 111 15 may be rotated to advance or retract the bracket 104 and its connected parts so as to adjust the position of the working tool such as shown at 99 in Fig. 2. Now it can be seen that the working tool such as 109 20 may be adjusted so as to bring the end thereof to a desired position by raising or lowering bracket frame 104. By turning the handle 123 so as to cam the plunger out of contact with the lead screw the arm may be 25 freely moved up or down and then secured in position by again turning the handle 123 to permit the spring 128 to cause the plunger to engage the lead screw 107. For finer adjustment the capstan head 11 may be engaged by inserting a pin in the holes in said head and turning the lead screw to raise or 30 lower the bracket frame 104 and its connected parts.

35 *Automatic lowering and raising device for the spindle and quill.*

The stroke of the working tool such as 99, 40 is made by raising and lowering the spindle 98 and the quill 103, this being accomplished through the rack 105 and the pinion 131 (see Fig. 29) which pinion is mounted upon a short shaft 132 journaled in a box 133 formed in the outer end of the frame 113. This box 133 has a clamping flange 134 for 45 clamping the forward end of the frame 113 to the bracket frame 104. Similar clamping lugs or flanges 135 serve to clamp the central parts of the frame 113 to the bracket frame 104. Thus the two frames 104 and 50 113 are rigidly connected together and move as one. The shaft 132 has a pinion 136 at its outer end and this pinion meshes with a gear sector or quadrant 137 mounted on a lever 138. The lever 138 is pivoted at its 55 central portion on the stud 139 and has a downwardly bent arm 140 upon the outer end of which there is a roller 141 forming a cam roller for the actuating cam 142. The stroke of the spindles and their working 60 tools may be varied in accordance with the requirements of the work by changing the cams 142 to give the desired stroke.

The tapping cams are generated by a uniform spiral corresponding to the pitch of the tap which it is designed to operate.

The cams are made of flat boiler plate the peripheries are the working surfaces. Connected to the cam 142 is a hub 143 by which it may be secured to the shaft 144 by a releasable connection 145 which is illustrated 70 more particularly in Figs. 29, 34 and 35. The cam shaft 144 extends through the rear part of the frame 113 which is divided to provide a pocket for the worm wheel 146. The shaft 144 is journaled in suitable boxes 75 or bearings 148 formed in opposite sides of the divided frame member 147. The worm wheel 146 is keyed to the shaft 144, whereas the cam 142 is secured to a hub 143 which is loose on said shaft 144. The shaft 144 is 80 provided with suitable heads 150 and 151 at its ends for preventing endwise play, and a bearing collar 152 is located between the cam 142.

The pin 154 is guided in a hollow stud 157 which is threaded into a recess in the hub 149. One end of the pin 154 extends into an aperture 153 in the shaft 144 (Fig. 34). A spring 158 tends to throw the inner conical end of the pin 154 into the sprocket 95 to key the hub to the shaft. The outer end of the guiding stud 157 is slotted by a diametrical cut as shown at 159 in Fig. 35, and a pin 160 which fastens diametrically 99 through the main pin or stem 154 slides in said slot and is adapted to be raised out of the slot by pulling on the button 155 against the spring 158. A shallow groove 161 is formed across the top of the guiding stud 157, so that the pin 160 when it is withdrawn may be dropped into this transverse shallow groove so as to hold the plunger against accidental turning and again keying the parts together.

By this quick releasable coupling, any 105 one of the spindles may be inactive so that it will not be reciprocated up and down with the other spindles when the entire machine is working and to provide a means of manual operation on any spindle by inserting hand lever into holes in collar, if desired.

The worm wheel 146 is driven by a meshing worm 164 which is splined to a vertical driving shaft 165 (see Figs. 28 and 29), this shaft having a cylindrical bearing in the boxes 166 and 167 which are formed as extensions of the same frame 113 which supports the bearing 148 for the worm shaft. The worm 164 is held against axial movement between said boxes 166 and 167 and due to feather or spline rotates with the driving shaft 165. This driving shaft 165, in addition to the bearings 166 and 167, has a bearing in a suitable box 168 which is mounted upon the carriage 67 (see Figs. 2 and 28). The bearing collars 169 and 170 are mounted on the shaft 165 above and below the box 168 and they restrain the shaft 165 against endwise movement. The collar 120 115 125 130

170 forms a part of a universal joint 171 between the shaft 165 and an intermediate shaft section 172 which is coupled through another universal joint 173 (see Fig. 2) to a short shaft section 174 which has a bearing in the box 175 mounted on the bracket 176. The shaft section 174 connects through a pair of bevel gears 177 and 178 to a horizontal shaft 179 which extends out radially from the main shaft 21, being connected through a bevel pinion 180 to the ring bevel gear 181 which is mounted on the main shaft 21.

Now it will be noticed from Fig. 6 that the ring bevel gear 181 is not driven directly by the main shaft 21, but is driven by a gear 182 having a bearing on said shaft 21, but driven at a speed determined by the counter-shaft 183 which carries the driving pinion 184, all as will be described more in detail later.

From the foregoing paragraph it will be apparent that the rotation of the shaft 165 driving the worm 164 rotates the worm wheel 146 and its connected shaft 144. If the quick detachable clutch 145 is released, the shaft 144 rotates idly. If the clutch acts to connect the worm shaft 144 with the hub of the cam 142, then the cam 142 is rotated at a predetermined rate to rotate the cam 142 and engage the roller 141 on the arm 140 of the lever 138. This outward movement of the roller 141 results in the gear sector 137 driving the pinion 136 and in turn the pinion 131 drives the rack 105 to plunge the lower end 100 of the spindle 98. The spindle may be raised by a spring or by means of a strap 186 running over a pulley 187 as shown in Fig. 2, and connected to a weight or spring for raising the hub 103.

While I have described only one of the working heads of the six shown in Fig. 1, it is to be understood that these working heads and their driving mechanisms extending to the main bevel gear 181 are all alike.

By referring to Fig. 5 it will be seen that the horizontal driving shafts 179 and 179' all similarly are geared through the bevel gears 180 and 180' to be driven by the same main gear 182 and its pinion 184 on the countershaft 183. It will be noted that there is not sufficient room on one of the bevel gears 181 to place all of the driven pinions 180, so two such bevel gears, one above and one below the main gear 182 are provided, and part of the driven shafts which I have numbered 179 (three in number), bear upon the upper bevel gear and the other three shafts which I have numbered 179, have their pinions bearing against the lower bevel gear 181'. This results in shafts 179 being driven in one direction and shafts 179' in the opposite direction. The worm shafts, however, are all

driven in the same direction. The inner ends of the shafts 179 and 179' are all suitably supported in boxes as shown at 186 in Fig. 5, these boxes having clamping flanges 187 for mounting them upon the inner barrel or frame member 188, which is bolted by suitable supporting feet 189 upon the lower frame plate 52, which forms a part of the base 53.

Now it will be apparent that as the main gear 183 is driven by the pinion 184 from the counter-shaft 183, the shafts 179 and 179' will drive the worm shafts 165 of each of the working heads in unison to advance the tools that are carried by the spindles 80 against the corresponding pieces of work which are in register with the working heads at a speed determined by the speed of the counter-shaft 183.

It is to be particularly noted that the releasable clutch members 145 are all adapted to drop into their notches simultaneously. This is for the purpose of having the working tools raised and lowered in unison. Any particular one of the working heads may be taken out of commission by releasing the quick release clutch 145, permitting the worm wheel shaft 144 to turn over idly.

Control mechanism for raising and lowering working tools.

In order to move the working heads, that is the spindles carrying working tools up and down in regular predetermined cycle, I provide control mechanism for varying in unison the speed of the cam shaft 144, which plunges the tools, such as 99 downward and raise them away from the work.

The machine receives its power from an electric motor 203, although any suitable source of power may be employed, driving through shaft 200 (see Fig. 6), this shaft 200 is connected to the main drive shaft 21 through a bevel pinion 201 which meshes with the main bevel gear 202. This main bevel gear or bull gear 202, meshes with six similar pinions identical with 201 in that they are connected to similar radial shafts 72 which drive the pulleys 71 and through belt 97 drive the spindles such as 98 shown in Fig. 2. The shaft 200 is simply a continuation of one of the shafts 72, extending directly to the motor 203, shown in Fig. 1.

The main bevel gear 202 is keyed as indicated at 203, to the main shaft 21, so that the shaft is driven at a constant speed by the motor 203.

Since the shaft 21 is driven at a constant speed, and since the tools on the working spindles are to be driven up and down at different predetermined rates, depending upon the operation to be performed, some means is necessary to change the ratio of drive between the main shaft 21 and the shafts 144 to which the cams are connected.

As previously pointed out these cam shafts 144 are driven by pinions 180 and 180', driven from bevel gears 181 and 181' connected to a main gear 182 which is loose on the shaft 21.

This gear 182 is driven by gear 184 on counter shaft 183. The gears 184 and 182 are constantly in mesh. The counter-shaft 183 is composite in structure and comprises the lower fixed parts 205 and the upper removable part 206. The lower or stub-shaft 205 has pinion 184 keyed thereto. It has bearings at 207 and 208 secured in suitable boxes mounted upon the inner frame or barrel 188. This frame or barrel is cut away as shown at the left of Figs. 2 and 6, so as to permit the change gears which will be described later, to be shifted as desired. The main housing or barrel 54, has an opening which is closed by a removable door 209, as shown at the left of Fig. 2 and Fig. 6. This door 209 has a hook 210 at its lower end, hooking over the lower edge of the opening and has a releasable hook or latch 211 connected to an outside releasing handle 212 for permitting the door 209 to be opened to change gears.

The upper end of the stub shaft 205 of counter-shaft 183, has a socket 213 formed with a square recess adapted to receive the squared end 214 of the removable shaft section 206. The upper end of the removable section 206 is supported in a readily separable bearing 215 (see Figs. 36 and 27). This bearing comprises a stationary yoke 216, having the fastening ends 217 and 218 bolted to the upper part of the inner housing or drum 188. A releasable yoke 219 cooperates with the stationary yoke 216 to form a closed bearing having the liner 220 of anti-friction metal surrounding the upper edge of the shaft 206. The movable yoke 219 is hinged at 221 to the stationary yoke 216, suitable perforated lugs being formed on the cooperating part, and the opposite end of the releasable yoke 219 is slotted as indicated at 222 to receive the stud 223 upon the outer end of which is fastened the wing nut 224 for holding the two parts of the bearing box together. This removable shaft section may be taken out of the bearing 215 to change gears to vary the driving ratio between the main shaft 21 and the cam shaft 44.

A series of driving pinions 225, 226, 227 and 228 all keyed to the main shaft 21. A series of cooperating counter-gears 229, 230, 231 and 232, which are removable from and attachable to the shaft section 206, are provided for cooperating with said driving pinions or gears 225, 226, 227 and 228. Thus, when the pinion 228 is employed in connection with the change gear 232, as shown in full lines Fig. 6, the drive from the main shaft 21 to the gears 228 and 232 to the

counter-shaft 183 and back to the gears 184 and 182 to the bevel gears 181 and 181', it will be seen that the drive to the cam shaft 144 is at the slowest rate. When the pinion 225 drives the counter-shaft through the removable gear 229, shown in dotted lines Fig. 6, the next higher speed of the cam shaft 144 is obtained. The third speed is obtained by the use of the pinion 226 cooperating with the removable gear 230, and the fourth or highest speed is obtained when the gear 227 cooperates with the gear 231. Thus it will be seen that cam shaft 144 can be driven at four different ratios with the structure shown. Obviously, a greater or less number of speed changes may be employed if found desirable.

Now, in order to advance the carrier 10 at intervals corresponding to the cycles of up and down motion of the working tools, the Geneva mechanism 27 must be timed to advance the carrier 10, while the working tools are in the raised position.

I shall therefore now describe the control of the carrier advancing mechanism.

Control mechanism for advancing the carrier.

The gear 226 which has heretofore been referred to as the gear employed in third speed, has an extending hub upon which is formed or otherwise secured, a sprocket pinion 235 (see Figs. 4 and 6). This sprocket is connected through a chain 236 with a larger sprocket wheel 237 keyed to the counter-shaft 238. The lower end of the counter-shaft is mounted in a bracket 239, which bracket is secured to the side of the inner housing or frame 188. The upper end of the shaft 238 is journaled in bearing 240 formed in the upper frame plate 26. A bevel pinion 241 is pinned upon the shaft 238 and is in constant mesh with a cooperating pinion 242 keyed on a shaft 243 running horizontally outward to drive the cam shaft 244. The horizontal shaft 243 has a bearing in a bracket 245 which is secured to the bottom of the top frame plate 26, as will be apparent from Fig. 6. The main drum or frame member 54 has an outwardly projecting hollow boss 246, providing a flat attaching surface for a bracket 247, for receiving and mounting the cam shaft 244. This bracket 247 is bifurcate and provides a pair of bearings 248 between which is mounted on said cam shaft 244, the cam disc 249. A removable cam ring 250 (see Fig. 7) is mounted on the disc 249 and is secured thereto by the four machine screws 251. In addition to the cam ring 250, which has a single cam projection thereon, I provide similar removable cam rings 252, 253 and 254 which have respectively 2, 3 and 4 cam projections thereupon at equiangular positions. The cam shaft 244 is driven

through a worm mounted on the shaft 243 and a worm wheel mounted on said cam shaft 244, these parts not being shown in detail but being mounted in a suitable housing 255 forming a part of the bracket 247. It will be seen that the shaft 238 is constantly driven at a fixed ratio with respect to the main shaft 21, and the shaft 243 which drives the cam shaft similarly is driven at 10 a uniform speed ratio in respect to the shaft 21. The result is that the cam shaft is driven at a speed which is constant and fixed ratio of the speed of the main shaft 21. The cam shaft is employed for controlling the operation 15 of the Geneva stop mechanism 27, which advances the carrier 10. The Geneva stop mechanism comprises the wheel 32 heretofore referred to, and the cam 33 heretofore referred to, and in addition the pinion 257 20 having the pin 258 carrying a suitable roller for entering the slots of the gear wheel 32. The cam 33 is cut away to provide the usual clearance for shifting the gear wheel 32 and for then entering the arcuate spaces 25 of the gear wheel 32 to hold the same accurately in fixed or stop position. The pinion 257 has a downwardly extending hub 259 which houses a spring 250, and is adapted 30 to receive the hub 261 (see Fig. 6) of the clutch member 262. This clutch member 262 has a series of square teeth 263 adapted to mesh with similar teeth 264 upon the top of the hub of the pinion 241.

The Geneva pinion 257 and Geneva cam 35 33 are pinned together to form a rigid or integral structure. The hub 259 of the Geneva cam and pinion structure is keyed to the hub of the clutch member 261 by a notch 266 in the first member and a stud or 40 projection 267 from the top of the lower member, these parts remaining in connected relation during the rise and fall of the clutch member 261 for engagement and disengagement of the teeth 264 and 265. The 45 clutching of these teeth together and consequently the transmission of motion from the shaft 238 to the Geneva cam and pinion, is controlled by a lever 268 pivoted on a vertical shaft 269 mounted in the hollow 246. 50 This lever has a relatively long hub on the shaft 269 suitably held in guided position to prevent endwise displacement of the lever on said shaft. The lever 268 bears at the end of the long arm a roller 270 mounted on a pin 271. The opposite end of the lever 268 bears at its end an adjustable contact screw or tappet 272 which is adapted to engage the cam tooth 273 and be moved in a counter-clockwise direction as viewed in Fig. 7, as 55 cam ring 250, is rotated. The roller 270 is adapted normally to ride in the groove 263 to hold the clutch member 261 in raised position against the tension of the spring 260, keeping the teeth 264 and 265 out of engage- 60 ment. When the cam tooth 273 of cam ring 250, shown in Fig. 7, engages tappet 272 on the adjacent end of the lever 268, the lever 268 is swung around in a counter-clockwise direction as viewed in Fig. 7, withdrawing the roller 270 from the groove 261, permitting the spring 260 to throw the teeth 264 and 265 into engagement, so that the Geneva cam and pinion are driven to set the carrier 10 forward 1 step or division of the Geneva gear 32. As soon as the rotation of the Geneva cam and pinion has been completed, the roller 270 is moved by means of a spring operating on the lever 268, to drop into the recess 273 so that further rotation of the clutch member 261 throws the clutch member upward to disengage the teeth 264 and 265. 65

By this means the carrier 10 is advanced at a rate, that is in steps per minute, corresponding to the timing of the working spindles up and down, so that for each forward step of the carrier 10 the working heads are carried down to the work to perform the operation desired and are then raised whereupon the carrier is again advanced by one 70 step. 75

Where it is desired to increase the number of operations per minute, as for example where the work to be performed by the various tools held in the various spindles, consumes less time, more operations per minute may be secured by increasing the number of steps of the carrier 10 per minute, and simultaneously increasing the number of up and down cycles of the working tools. For example, the cam rings 252, 253 and 254 may be mounted upon the cam plate 249 to increase the number of steps per unit of time and at the same time the change gears on the counter-shaft 183 are to be substituted 80 90 to keep pace with the increased rate of advance of the table or carrier 10. 100

This change of cam plates is readily accomplished by means of the four machine screws 251 on the cam plate 249 for changing the cam rings. The change of the gears is readily accomplished through the use of the removable shaft section 206 heretofore described. 105

It is to be observed that even if the tool plunging and carrier advancing mechanism is speeded up or slowed down the tool speed, i. e., the cutting speed of the tools themselves should not be varied. Hence the ratio of motor speed to spindle speed should remain the same or if varied should be varied to produce the proper cutting speed independently of the rate at which operations are performed or the length of the cut of an operation. 115

Hence if any common speed changing device were employed, it must be inserted at 120 a point subsequent to the take off of the spin-

idle drive, i. e., beyond the main bevel gear 202 or the main shaft 21.

Chucks for the work.

- 5 The work holders or chucks 41 shown generally in Fig. 1, employed in connection with the holding of the piece shown in Figs. 46, 47 and 48, are all alike and are carefully indexed on carrier 10 so as to preserve accurately 10 the angular spacing, so that at each position of the carrier 10 the work will coincide with the working head. Each work holder or chuck comprises a plate 275 formed in the carrier 10. The holes or stops 277 15 are carefully laid out to preserve the correct angular position, and the plate 275 is then squared up so as to bring the work in proper alignment with the working head. The plate 275 has posts or legs 278 at the 20 corners and at intermediate positions, as may be seen from Fig. 16, and the base plate is held down on the carrier 10 by means of the small clamp 279 in the well-known manner. For supporting the small levers shown 25 in Figs. 46 to 48, so that the hole 16 may be drilled and tapped, I provide a shouldered pin 280. The split clamp before it is split, fits over said pin and rests upon the shoulder. The opposite end of the lever, 30 which is split in a horizontal plane as the piece is shown in Figs. 16 and 17, fits over bracket 281 to provide support against movement in a vertical direction. A spring 35 pressed pawl or finger 282, which is pivoted on a pin shown in dotted lines at 283 in the plate 275, holds the lever firmly and accurately in place. It will be noted that the hole 16 in the lever lies radially in line with the index hole 277, so that the working tool 40 which lies in the same radial line may be accurately centered to drill or tap said hole. It will be noted that the solid boss which later forms the split clamping lug 13, over-lies the slot 284 formed in the shouldered 45 pin 280. The slotting saw, later to be described, cuts through the lug to form the split clamp 13.
- A second holding device or vise, shown 50 at the left of Fig. 16 and 17, is adapted to hold the work so as to permit counter-boring and tapping the hole through the lugs 13. To this end a V-shaped groove 285 is formed in the side of a post or lug 286, which is mounted upon the plate 275, and a hollow 55 hardened pin 287 is set adjacent to said groove so as to form a vertical support for the adjacent end of the lever comprising the lugs 13 which are guided horizontally into the groove 285 and held in that position by 60 the spring pressed finger 288 which is pivoted on a pin 289 in the plate 275. The opposite end of the lever rests on a saddle 290 which supports the lever against lateral movement. A pair of pins or posts 291 65 assist in holding the central part of the lever

in place. A stripping plate 292 is fastened on top of the block or post 286 and overlies the edge of the upper lug 13, so that as the tools are withdrawn from said lugs the piece will be held down or stripped from such tool. 70

Now, as the machine is set in Fig. 1 working heads 57, 58 and 59 register with the hole 18 in the split clamp which at this point is still unslotted. That is to say, a piece is chucked in the inner vise which I 75 will indicate as 292 and this piece is then sent forward in steps and is operated upon by working heads 57, 58 and 59 to perform first a through drilling operation to form the hole 18 by the working head 57. In the next 80 position or station, the working head 58 counter-bores the hole and at station 59 the lower part of the hole is tapped by an automatic tapping chuck well-known in the art. It will be noted that the centers of the spindles or working heads 57, 58 and 59 are all arranged at a common radius R , so that they operate on hole 18 as above explained. The centers of the spindles in working heads 60, 61 and 62 are arranged at a greater radial 85 distance R' , as shown in Fig. 1, so that these working heads may operate upon the work as it is held in a vise 293, which, as will be apparent from Fig. 1, as arranged at a greater radial distance from the center of 90 the carrier 10. Working head 60 reams out and counter-reams the hole 16 which was originally formed by punching when the blank was made up. Working head 61 then 95 taps the lower or smaller side of the hole and working head 62 slots the split clamp by sawing the slot 17.

Thus the blank pieces are chucked in the vise 292 and are sent past the working heads 57, 58 and 59 in successive steps to receive 100 at such stations the proper operations, whereupon the remaining steps past the working heads 60, 61 and 62 are idle with respect to the piece in the chuck 292. When the chuck arrives at the two blank positions 105 shown in Fig. 1, the piece is released from the vise 292 and placed in the vise 293 and at the same time a fresh blank is inserted in the vise 292. Thereupon the fresh blank goes through the operations at the stations 110 corresponding to working heads 57, 58 and 59. The piece in the vise 293 goes through the operations performed at stations corresponding to working heads 60, 61 and 62 whereupon the chuck arrives at the first free 115 position. The finished piece is then released from the chuck 292. The semi-finished piece is transferred from the vise 292 to the vise 293, and a fresh piece inserted in the vise 292 during the two steps of the carrier at 120 the two stations where no working heads are provided.

I shall now describe briefly the slotting saw, as an example of a working tool which may be employed to perform an operation 125

upon the piece under consideration, and differing somewhat from rotary tools such as drills, reamers, et cetera.

5 *Slotting tool.*

Referring now to Figs. 38 to 41, I show a slotting saw such as is used in the machine illustrated at the station corresponding to working head 62. A head or frame 296 has 10 a socket 297 adapted to receive the enlargement 101, which carries the bearings for opposing the thrust of the lower end 100 of the spindle, such as 98. The socket 297 is split at 299 and the clamping gears 300 are adapted 15 to be clamped together by means of the bolt 301. Upon the opposite side which faces radially outward from the center of the carrier 10, ears 302 are provided, these ears being spaced apart far enough to permit 20 entry of the rack 105 by which the spindle is moved up and down. Semi-cylindrical filler pieces 104, which form a clamping sleeve above the bearing 101, are dropped into the top of the socket 297 and rest 25 against the shoulder formed by the ring 101 so as to hold the working head 296 in proper position. The working head 296 has a tapered shank 305 mounted on the upper end of a spindle 306 which spindle is supported 30 in ball-bearings 307 in the head 296. A pinion 308 is secured upon the lower end of the spindle 306 and this pinion 308 meshes with a gear 309, the gear being keyed to a counter-shaft 310. The counter-shaft 310 35 has anti-friction bearings 311 in the head 296 immediately above the gear 309 and has a plain bearing at 312 with a suitable shoulder 313 formed on the upper end of the spindle to support the weight of the parts on the 40 shaft 310. At its lower end the counter-shaft 310 has a bevel pinion 314 meshing with a bevel gear 315, which gear is rigidly secured upon an arbor 316, this arbor having bearings at its ends in the split boxes 317 45 and 318. A suitable collar 319 is formed upon the arbor 316 and a clamping ring 320 is threaded upon the spindle adjacent the collar 319, so as to grip between the ring and the collar a slotting saw 321. This spindle 50 with its slotting head 296 is raised and lowered in the same manner as the other tools on the working heads.

It will be noted that in Figs 38 to 41 the slotting saw 321 is placed directly axially in 55 line with the spindle. By substituting a different arbor 316 with the shoulder or collar 319 placed at a different point along the length thereof, the slotting saw 321 may be located at any desired position within its 60 limit. It will be noted in Fig. 16 that the slot 284 is off-set with respect to the hole 216 and the indexing hole 277. This is secured by substituting a different arbor 316.

In the present machine each spindle may 65 be independently adjusted to work on its

own center, by radial movement in or out. It may be independently adjusted for depth of cut by its own cam. It is possible, for example, to tap a hole in one piece and another hole of a different screw pitch by the adjacent or another spindle by employing suitable cams. The cams are preferably formed by flat boiler plate stock, the periphery being the working face. It is possible to drill a small diameter hole faster than a large diameter hole, and the throw of the controlling cams 142 should be laid out in proportion. In the same way the advance of a tap for a coarse thread determines a more rapid throw by the cam than in the case of a fine 80 thread. In like manner, the particular rate of advance of the cutting tool is governed by the cam 142.

The present machine is a universal machine and can do within limits anything that 85 can be determined by the use of controlling cams.

In regard to the use of parallel sets of speed changing mechanisms instead of a single set, I wish to point out that in the present machine I am able to drive the Geneva mechanism at a uniform rate of speed which is desirable, as it permits the shift from station to station to occur in minimum time. If I employ a single change 90 speed mechanism, I still propose to reach back from the Geneva mechanism to the main driving shaft for operation of said Geneva mechanism.

100

Résumé.

The operation of the machine above described is believed to be apparent from the foregoing detailed description.

While I have shown the machine as set up for a particular piece of work, it is to be understood that the work may be widely varied and tools may be substituted and adjusted accordingly. The machine is particularly useful for such operations as are required on the bodies of carburetors and the like.

The operations to be performed may be performed in groups of any number within the limit of the machine, and the machine is not to be limited to any particular number of working heads shown. It is also to be understood that while I have shown the working heads at definite radial stations at 115 equiangular positions, and have shown these heads as movable in and out radially, it is to be understood that the heads may, if desired, be moved laterally without departing from the invention. In general, it will be found easier where the adjustment is limited to one dimension, because then accurate indexing 120 can be preserved.

I do not intend to be limited to the details shown or described, and while I have shown 125 adjustment and details of a particular char-

105

acter, it is to be understood that these may be varied within the limits of the invention except as such details and limitations may appear in the appended claims.

5. I claim:

1. In combination, a table adapted to be intermittently advanced by rotary motion, a plurality of working heads stationed at equidistant stations about said table or carrier, 10 said heads having spindles disposed vertically above the table or carrier, a common central vertical shaft below the table or carrier, a plurality of radial drive shafts connected to the common central vertical shaft 15 and having a belt-driven means for operating the spindles, and a driving member connected to one of said radial shafts for driving the central shaft and the radial shaft in unison.
20. 2. In combination a common vertical shaft having a bevel gear, a plurality of radial shafts having a bevel pinion, a circular table or carrier, a plurality of working heads stationed about said table or carrier, and having spindles disposed vertically above the same, driving means between said radial shaft and said spindle, driving means for the main vertical shaft, and means between said main vertical shaft and said table for intermittently advancing the table.
3. In combination a horizontal table pivoted on a vertical axis, a plurality of vertical spindles mounted at equidistant stations about said table, a main shaft below 35 the table, means connecting the main shaft with said spindles, driving means connected to main shaft, means for intermittently advancing the table in equiangular steps, and means driven from the main shaft for causing spindles to work upon the articles upon the table between advances of the table.
4. In combination a horizontal circular table having a vertical axis, a main shaft lying in line with the axis of the table and 45 below the same, a plurality of vertical spindles above the table, said spindles having working tools, the table having means for chucking pieces upon which a plurality of operations are to be performed, means for driving said main shaft, means connecting the main shaft to said spindles to drive spindles at a uniform rate of speed, means connecting the main shaft and the table intermittently for rotating the table by equiangular steps, and means in said connection for controlling the number of steps per minute by which the table is advanced.
5. In combination a frame, a driving pulley for a spindle mounted in the upper 60 end of the frame, a spindle projecting vertically through the driving pulley, a quill for the spindle, an adjustable frame mounted on the first frame for supporting the quill, means on said adjustable frame for plung-

ing the quill and its spindle, and adjusting means for varying the height of said adjustable frames, said adjusting means comprising a vertical lead screw secured to the main frame and a quick releasable nut secured to the adjustable frame.

6. In combination a goose neck frame having a driving pulley for a spindle at its upper end, a vertical driving spindle projecting therethrough, a quill for the spindle, an adjustable frame mounted on the goose neck frame, a rack for the quill, a pinion for the rack, means for driving the pinion, including a second pinion and gear quadrant, a lever connected to the gear quadrant, a cam mounted rotatably on the adjustable frame, 75 a gear wheel carried on the shaft of the cam and having a releasable connection with the cam, a second gear wheel meshing with the first gear wheel, said second gear wheel being also carried on the adjustable frame and a vertically splined driving shaft for the second gear wheel, said second gear wheel being movable in nonrotative relations along the spline shaft as the adjustable frame is moved up or down.

7. In combination a goose neck frame having a driving pulley, a spindle splined to the pulley, a quill and adjustable frame mounted slidably on the goose neck frame for vertical adjustment, said quill having a rack and pinion for plunging the spindle, a pinion and quadrant for driving the pinion, cam actuated means for driving the quadrant, a vertical driving shaft along which the adjustable frame is movable and gears mounted to the adjustable shaft for driving the cam-actuated means, and a lead screw on the goose neck frame and a quick releasable nut on the adjustable frame for adjusting the height of the adjustable frame.

8. In combination a main machine frame, a bracket on the main machine frame having a guide, a slide on said guide, a driving shaft extending in alignment with the guide, a pulley supporting frame rigidly connected to the slide and supporting a pulley splined to the first shaft, a goose neck frame mounted on the slide, a spindle supported in vertical relations to the goose neck frame, a quill for the spindle, adjustable frame on the goose neck frame, cam actuated means for plunging the spindle, a vertical shaft carried by the slide for driving the cam actuated means and a flexible shaft for driving said latter shaft.

9. In combination a main machine frame, a bracket secured thereto, a guide on the bracket, a slide on the guide, a pulley supporting frame on the slide, a shaft parallel to the guide, said pulley supporting frame having a pulley splined on the shaft, a goose neck frame mounted on the slide, a vertical spindle supported by the goose neck frame,

- 5 said goose neck frame having a driving pulley for the spindle connected to said first pulley on the bracket frame, a vertically adjustable frame slidable on the goose neck frame, 65
 5 plunging means for the spindle carried by said adjustable frame, a vertical driving shaft for said plunging mechanism, said driving shaft being longitudinally splined to drive the plunging means in any desired
 10 position of the adjustable frame.
10. In combination a horizontal table rotatable intermittently about a vertical axis, a main drive shaft below the same, a spindle mounted above the table, for engaging successive pieces of work mounted upon the table, means for plunging the spindle to cause engagement of a tool carried thereby with the work on the table, a main drive shaft below the table, a change gear set connecting said main drive shaft with the plunging controlling member, and means connecting the main shaft to the spindle for driving the same at a uniform speed for all speeds of the plunger driving mechanism. 70
- 15 11. In combination a horizontal table having a vertical shaft, a main shaft in alignment with the shaft of the table, a spindle above the table, means for driving the spindle from the main shaft, said spindle having a tool for operating upon the work on the table, means for bringing the tool and the work on the table into operative engagement, said means including change speed mechanism for varying the rate of engagement of the tool with respect to the work, said change speed mechanism including a plurality of gears on the main shaft keyed thereto, a counter-shaft and selectable gears for the counter-shaft adapted to selectively 75
 20 engage the gears on the main shaft. 80
- 25 12. In combination a table, an upper frame plate, a central shaft for the table having a bearing in the upper frame plate, a plurality of work supporting chucks mounted on the table, a horizontal thrust bearing between the table and the upper frame plate, said thrust bearing being substantially in alignment with the work holding chucks, means for operating on the work 85
 25 held in the chucks and means under the top frame plate for intermittently advancing the table in angular steps. 90
- 30 13. In a machine of the class described, a main frame comprising a top frame plate, a base and a barrel connecting the top frame plate and the base, a circular rotary table having a bearing in the top frame plate, a thrust bearing between the bottom of the table and the top frame plate, a plurality of working spindles mounted on brackets secured to the barrel, a main shaft having its upper end telescoped with the shaft of the table, having its lower end supported in the base, means connected to the main shaft for 95
 35 driving the spindle of the working heads, and means for intermittently clutching the main shaft to the table shaft to advance the table in angular steps. 100
- 40 14. In combination a frame comprising a barrel, a top frame plate, a base, a table having a central shaft mounted in the top frame plate and having anti-friction thrust bearings between the bottom of the table and top of the top frame plate, a plurality of brackets secured to the barrel, a plurality of adjustable working heads mounted on said brackets, said working heads having operating spindles adapted to engage the work on the table, a main shaft having a bearing co-axial with the bearing of the table at its upper end and having a bearing in the base at its lower end, means connected to the main shaft for driving the spindles at a constant rate, means connected to the main shaft for driving the table intermittently at a predetermined rate, plunging means for plunging the spindles of the working heads, and means connected to the main shaft for operating said plunging means at a predetermined collective rate. 105
- 45 15. In combination a frame having a top frame plate, a barrel and a base, a table having a central bearing in the top frame plate and having a thrust bearing between the bottom of the table and the top frame plate, a Geneva gear connected to the table shaft below the top frame plate, a main driving shaft axially in alignment with the table shaft, a counter-shaft parallel to the axis of the aforesaid shaft, Geneva pinion and cam mechanism loosely mounted on said counter-shaft, a controlling cam shaft, a cam on the cam-shaft controlling the clutching of said counter-shaft to the Geneva cam and pinion, and quick releasable means for 110
 50 changing the cam to control the rate of advance of the table. 100
- 55 16. In combination a frame comprising a top plate, a barrel, a base, said barrel having an open side, a table having a central shaft journaled in the top plate, a thrust bearing between the table and the top plate, a main shaft axially in alignment with the table shaft, a bull gear connected with the main shaft, a plurality of working heads mounted on the barrel and having spindles extending above the table, driving connections from the bull gear to the spindles for driving the spindles at a uniform rate, a plurality of selectable driving pinions on the main shaft, a counter-shaft having a fixed portion, a removable portion, a plurality of change speed gears for the removable portion for connecting one of the selectable pinions on the main drive shaft with the counter-shaft, a pinion on the fixed part of the counter-shaft, a loose gear on the main shaft meshing with said latter pinion 115
 60 120
 65 125

- and a plurality of shafts geared to said loose gear, and spindle plunging mechanisms connected to said latter shaft.
17. In combination a frame, a table supported by the frame for rotation about a vertical axis, a main shaft axially in alignment with the axis of the table, a working spindle mounted above the table, means for plunging said spindle to bring the tool of the spindle into engagement with the work on the table, a plurality of selective pinions on the main shaft, a counter-shaft, a plurality of selective gears adapted to be mounted on the counter-shaft for engagement with any one of the selected pinions, a pinion fixed on the counter-shaft, a loose gear meshing therewith mounted on the main shaft, and means connecting said loose gear with the spindle plunging mechanism.
18. In combination, a rotatable table, having a plurality of pieces of work positioned thereon in a circular path at a given radius from the center of said table, and a plurality of pieces of work positioned in another circular path at a different radius from the center of the table, a plurality of work performing units including tools positioned over the table adapted to act on the said pieces of work, said concentric path arrangement enabling the size of the table to be maintained at a minimum and eliminating possible interference between said work performing units, means for intermittently advancing the table, and means for causing the tools to be applied to the pieces of work during the periods of time the table is stationary.
19. In combination, a rotatable table, having a plurality of pieces of work positioned thereon in a circular path at a given radius from the center of said table, and a plurality of pieces of work positioned in another circular path at a different radius from the center of the table, a plurality of work performing units including tools positioned over the table adapted to act on the said pieces of work, means for intermittently advancing the table, and means for causing the tools to be applied to the pieces of work during the periods of time the table is stationary, the said pieces of work in one circular path being supported in a plane different than that of those in the other circular path.
20. In combination, a rotatable carrier, a first work holder positioned thereon at a given radius from the center of the carrier, a second work holder positioned thereon at a different radius from the center of the carrier, said carrier moving through concentric circular paths, a plurality of tools stationed over the table and spaced angularly from each other, and means for intermittently advancing the carrier to subject the work in the holders to the action of the tools.
21. The method of subjecting a plurality of pieces of work supported on a rotatable table to a plurality of tools for performing work thereon which consists in placing the pieces in different concentric paths, indexing the table, and during the periods of time the table is stationary, removing a piece from one path and positioning it in a different plane in another circular path.
22. In combination, a rotatable table for carrying a plurality of pieces of work on which a plurality of operations are to be performed, said table being adapted to be intermittently advanced, and a plurality of staggered work holders positioned on the said table in concentric circular paths the holders in one path being adapted to support the work in one plane with respect to the holders and the holders in another path being adapted to support the work in a different plane with respect to the holders.
23. In combination, a table adapted to be intermittently advanced by rotary motion, a plurality of working heads stationed at equidistant stations about said table, said heads having spindles disposed substantially vertically above the table, a substantially vertical shaft positioned below the table in axial alignment therewith, a plurality of radial drive elements connected to the said shaft for operating the said spindles, and a driving member connected to one of said radial elements for driving the central shaft and the radial element in unison.
24. A rotatable table, a plurality of working heads stationed at equidistant stations above said table, said heads having spindles disposed substantially vertically above the table, a substantially vertical shaft associated with the table in axial alignment therewith, a plurality of radial elements extending from the said shaft and driven thereby, driving connections between the said radial elements and the said vertical spindles and means connecting the said vertical shaft with the said table for intermittently advancing the table.
25. In combination, a substantially horizontal table rotatable about a vertical axis, a plurality of work performing tools positioned at equidistant stations about the table, a main driven element positioned below the table, driving mechanism connecting the main element with the said tools, driving means connecting the main element to the table for intermittently advancing the same, and means connecting the tools to the main driving element for raising and lowering the tools automatically between advances of the table.
26. In combination, a revolvable table having positioned thereon a plurality of work holders, work performing units including tools disposed and stationed along the said table and immediately over the said holders, a main driven shaft disposed below the said

- table in axial alignment therewith, driving connections between the said main shaft and the said tools for rotating the tools including a plurality of elements extending radially from the said shaft, means including a Geneva movement connecting the said shaft to the table for intermittently advancing the table, connections between the said shaft and the said tools for intermittently raising and lowering the said tools during the period of time the table is stationary, and means for enabling the varying of the intermittent action of both the table and the tools.
27. In combination, a revolvable table having positioned thereon a plurality of work holders, work performing units including tools disposed and stationed along the said table and immediately over the said holders, a main driven shaft disposed below the said table in axial alignment therewith, driving connections between the said main shaft and the said tools for rotating the tools including a plurality of elements extending radially from the said shaft, means including a Geneva movement connecting the said shaft to the table for intermittently advanc-
- ing the table, connections between the said shaft and the said tools for intermittently raising and lowering the said tools during the period of time the table is stationary, and means for enabling the varying of the intermittent action of both the table and the tools, said latter means including change speed gearing associated with the said main shaft.
28. In combination, a rotatable table for carrying a plurality of pieces of work on which a plurality of operations are to be performed, said table being adapted to be intermittently advanced, and a plurality of staggered work holders positioned on the said table in concentric circular paths, the holders in one path being arranged to support the pieces of work for the performance of given operations thereon, and the holders in another path being arranged to support the pieces of work for the performance of additional operations thereon after the work has been acted on in said first path.

In witness whereof, I hereunto subscribe my name this 12th day of August, 1924.

LOUIS H. STEIN.
